UNITED STATES PATENT OFFICE.

ABRAHAM ISAAC KAPLON, OF BRUNSWICK, MARYLAND.

RADIATOR THERMOSTAT.

Application filed July 2, 1920. Serial No. 393,680.

To all whom it may concern:

Be it known that I, ABRAHAM ISAAC KAPLON, a citizen of the United States, and a resident of Brunswick, in the county of 5 Frederick and State of Maryland, have invented a new and useful Improvement in Radiator Thermostats, of which the following is a specification.

My invention relates to improvements in 10 radiator thermostats, and it consists in the constructions, combinations and arrangements herein described and claimed.

An object of my invention is to provide a 15 radiator thermostat including an incandescent lamp arranged to be lighted upon completion of the electric circuit when the mercury in the tube reaches a predetermined high or dangerous point indicating excessive heating of the engine, so that the operator of the engine is warned in time.

Another object of the invention is to provide a radiator thermostat as described, in which the incandescent lamp is so embodied and in which the parts are so arranged, that 25 the device may be taken off and temporarily used as a search light for hunting trouble about the engine.

Other objects and advantages will appear in the following specification, reference being had to the accompanying drawing, in which:

Figure 1 is a side elevation of the radiator thermostat, parts being shown in section.

Figure 2 is an elevation of the thermostat 35 as it appears from the seat of the car, parts being shown in section.

Figure 3 is a cross section on the line 3—3 of Figure 2.

Figure 4 is a detail section of a portion of 40 the battery barrel; and

Figure 5 is a perspective view illustrating the application of the device as a portable search light.

In carrying out my invention I provide a 45 body 1 having the usual circular sight opening 2 near the top, through which the rising mercury 3 in the thermometer tube 4 becomes visible. The principal elements of the thermostat are of a well known construction, and 50 the thermostat includes an externally threaded pendent sleeve 5 extending through the radiator cap 6 where it is secured in place by the nut 7 which is screwed upon the threaded sleeve as shown, into contact with the upper wall of the recess in the cap 6.

The lower end of the thermometer tube 4

extends down into the sleeve 5 as shown, and when excessive heat is generated by the engine either by some internal difficulty or by the lowering of the cooling water to a dangerous level, the mercury 3 will rise in the tube 4 past the sight opening 2.

When the mercury 3 thus rises, it reaches a pair of contacts 8 fixed in the glass, and closes the electric circuit that lights the lamp 9. Each contact 8 consists simply of a shank embedded in the glass of the tube 4 when the glass is yet soft, with a head on the inside and an ear 10 on the outside. The ear 10 of each contact 8 has a suitable nut 11 by means of which the wires are secured in place.

A lamp socket 12 is embedded in an insulating bushing 13 in the top of the body 1. The socket 12 includes an ear 14 with a nut 15 beneath which the wire 16 from the ear 10 at the left side, is secured. Another wire 17 is secured between the nut 15, this wire leading to the fixed contact 18 of a push button which will presently be described.

A battery 19 consisting of a suitable number of cells, is located in the battery barrel 20 and furnishes the current for lighting the lamp. A wire 21 diagrammatically illustrated in Figure 2, leads from the positive pole of the battery to the contacts 8 at the right. The negative pole of the battery is grounded to the metallic portion of the body 1. One terminal of the lamp 9 is also grounded to the metal portion of the body 1. Upon rising of the mercury 3 in the tube 4 as previously explained, until the mercury bridges the contacts 8, the electric circuit is completed and current from the battery flows thus: Over the wire 21, through the contacts 8, over the wire 16 and through the lamp socket 12 to the metallic body 1 and from thence back to the negative pole of the battery.

The cells 19 of the battery are held in place in the barrel 20, by a screw cap 22 as illustrated in Figure 4. The arrangement of the internal contacts between the cells of the battery and the barrel 20, may be of any ordinary arrangement, the complete illustration of these contacts within the barrel being thought to be unnecessary.

A hood 23 partly covers the lamp 9 and serves as a reflector for throwing the rays of light down upon the exposed portion of the thermometer tube 4. The hood 23 may be secured in place by any suitable means, a pair of ears being shown in Figure 2. In-

cidentally it may be mentioned, that the battery barrel 20 is secured upon the body 1 in the rounded portion of the body where the circular flange which engages the radiator cap 6, meets the upper portion of the body. It will be readily observed that in order to embody the elements of my invention in the ordinary radiator thermostat, radical changes in the construction of the thermostat are unnecessary.

Another feature of the invention consists of the removability or portability of the thermostat and the arrangement of the electric circuit so that the device may be employed as a spot light for hunting trouble about the engine. Referring to Figure 2, it will be observed that a push button 23 is arranged to press a movable contact 24 upon which the button is mounted into engagement with the fixed contact 18. The contact 18 is insulated from the body 1 as indicated, and when the button 23 is pressed, current flows from the positive pole of the battery over the wire 21, over the branch wire 21² to the movable contact 24, through the fixed contact 18 and the wire 17 to the metallic socket of the lamp 9, and thence back to the negative pole of the battery through the grounded connections.

In employing this feature of the invention, the radiator thermostat is of course taken off and used as indicated in Figure 5. It will be appreciated at once, that the average motorist does not always have a pocket flashlight handy. It often occurs that a light by which the often escaping gases about the engine may not be ignited, becomes invaluable. In such instances, the thermostat may be taken off and the lamp 9 employed as a spot light in the manner just suggested.

The operation of the device is thought to be fully understood from the foregoing description; a brief review thereof is thought to be of advantage however. The principal advantage in providing the incandescent lamp 9 at the top is, that the mercury column 3 is illuminated when it reaches a predetermined high and dangerous level in the tube 4. Heretofore, there was no means by which the driver of the car could ascertain the standing of the mercury column in the tube. Consequently, dangerous conditions have often risen. By providing the contacts 8 with the exposed buttons inside of the tube, the mercury upon rising in the tube and bridging the contacts, serves to complete the electric circuit and light the lamp, thus not only giving the driver a visible danger signal, but also indicating the standing of the mercury itself.

In actual practice, the contacts 8 will be located at the required places in the tube 4.

Obviously, if the situation wherein they are shown in the drawing is not correct, they may be placed lower. The lamp 9 is intended to be used both in day-time and at night. Of course the illumination of the mercury column when it reaches the predetermined high and dangerous point will not be as conspicuous in the daytime as at night, but the advantages derived from permitting the lighting of the lamp in the daytime are sufficient to overcome any otherwise elaborate arrangement for cutting out the lamp in the day-time.

While the construction and arrangement of the radiator thermostat as illustrated in the accompanying drawing is that of a generally preferred form, obviously, modifications and changes may be made without departing from the spirit of the invention or the scope of the claims.

I claim:

1. A radiator thermostat comprising a body, a thermometer tube containing mercury mounted on the body, a battery barrel mounted outside of the body adjacent to the base of said tube, an incandescent lamp mounted on the body at the head of the tube, a hood carried by the body and disposed over the lamp to reflect light upon the tube and reveal the position of the mercury, an electrical circuit embracing contacts in the tube, a battery in said barrel and the aforesaid lamp, said mercury being adapted to rise to bridge the contacts and close said circuit; and push button contacts situated on top of the body enabling closing the circuit independently of said mercury and adapting the thermostat to the use of a portable flashlight.

2. A radiator thermostat comprising a circular body having a sight opening and a sleeve enabling securing the body to a radiator cap, a thermometer tube entering the sleeve and extending past the sight opening, a battery barrel mounted transversely on the outside of the body and adjacent to the sleeve, means engaging the barrel to keep a battery in place, an incandescent lamp situated at the head of said tube, means by which the lamp is mounted on the body, a hood carried by the body and disposed over the lamp to reflect light downwardly, an electrical circuit comprising a battery in the barrel and contacts in the tube, said contacts being adapted to be bridged by mercury in the tube to light the lamp which is included in said circuit, and push button contacts located adjacent to the rim of the body near the top enabling ready closure thereof by grasping the thermostat and using it as a portable flashlight.

ABRAHAM ISAAC KAPLON
